UNITED STATES PATENT OFFICE.

HAMILTON LEE DAVIS, OF MARTINSBURG, WEST VIRGINIA, ASSIGNOR TO THE INTER-
WOVEN MILLS, INC., OF NEW BRUNSWICK, NEW JERSEY, A CORPORATION OF NEW
JERSEY.

CIRCULAR-KNITTING MACHINE.

Application filed September 30, 1925. Serial No. 59,470.

My invention consists in the novel features hereinafter described, reference being had to the accompanying drawings which illustrate one embodiment of the same, selected 5 by me for purposes of illustration, and the said invention is fully disclosed in the following description and claims.

I have illustrated my invention applied to a split foot stocking knitter of the kind 10 illustrated and described in the Letters Patent of the United States granted to R. H. Lawson, No. 1,458,833, dated June 12, 1923, and assigned to Hemphill Company, which is an improvement upon the well known 15 Banner machine illustrated for example in the U. S. Letters Patent to Hemphill, No. 933,443, dated September 7, 1909, and I will describe my present invention as applied to this type of machine, although I wish it 20 to be understood that it may also be employed in machines of other kinds.

In the operation of seamless stocking knitters, in which provision is made for varying the size of the knitted stitch in different 25 courses, by elevating the knitting cam or cams so that the needles will draw a smaller loop, it is frequently found that when it is desired to increase the size of the stitches, or to restore them to normal size, and the 30 stitch cam elevating mechanism recedes for that purpose, the slide or other movable support for the secondary knitting cam or cams fails to descend as intended, with the result that succeeding courses are knit with a 35 smaller or tighter stitch than intended. As the length of various portions of the stocking, as the leg and foot portions, for example, is determined by the pattern mechanism on the basis of a pre-determined number of circular courses, the result of knitting 40 these courses or a plurality of them, with a smaller or tighter stitch produces a shorter fabric than intended and results in the production of a defective product. Various expedients have been resorted to for the purpose of overcoming this defect, such as re-tracting springs, for example, but these have 45 not proved reliable at all times and as a result, it frequently happens in a commercial 50 hosiery factory that a large number of pairs of stockings will be turned out by a machine or machines and be found upon inspection to be too short in the foot, to come within the intended size. This has made it neces-

sary in actual practice to inspect each stocking turned out on the machines and measure the same in order to be sure that no defective product is delivered. Obviously, when the machines are in operation at high speed, it is difficult, if not impossible, to ascertain 55 whether or not the knitting cams are descending at the proper point in the cycle of operation in the machine, by an inspection of the machine itself, and moreover, the machine may operate correctly part of the time and at other times the secondary knitting cams may fail to descend. As a matter of personal investigation and experiment, my present invention has been evolved for the 60 purpose of overcoming this difficulty, and it consists essentially in providing in such machines means for positively pulling down the secondary knitting cams to their proper 65 knitting positions for the longer stitches throughout the instep when released from 70 the action of the elevating mechanism.

Referring to the accompanying drawings, in which I have illustrated so much of the stocking knitter as is necessary, for an understanding of my present invention, 75

Fig. 1 is a side elevation, partly broken away, of a stocking knitter showing my invention embodied thereon.

Fig. 2 is an enlarged detail sectional view illustrating the means for supporting the 80 knitting cams and for elevating the same.

Fig. 3 is a partial elevation of the parts illustrated in Fig. 2, looking in the direction of the arrow in that figure, or in other words, from the interior of the cylinder.

Fig. 4 is a detail view showing my improved cam and the lever and connecting rod operated thereby.

The construction and operation of the Banner machine is so well known that it 90 will not be necessary to describe more than the parts directly affected by my invention, it being understood that the other parts not mentioned are of the usual construction described in the patents heretofore mentioned, 95 and particularly in the Lawson patent.

Referring particularly to Figs. 2 and 3, 62 and 63 are the secondary knitting cams, or stitch forming cams, for drawing down the needles and forming the stitches in the 100 reciprocating work employed during the knitting of the instep on the long butt needles, 64, 65 and 66 being the usual guide or 105

guard cams. The knitting cams, 62 and 63, are adjustable vertically, and to this end are mounted on a plate, 67, which is attached to a slide, 68, adjustably arranged to move vertically in a bracket, 69, secured to the frame, 1, by screws, 70. The slide, 68, is held in position in the bracket by screws, 71, extending through elongated slots in the bracket. Suitable means, such as an adjusting screw, 72, are provided for limiting the downward movement of the slide, with respect to the bracket, and thus limit the position to which the cams, 62 and 63, may be lowered, and thus determining the largest or the smallest size stitch which may be drawn. For the purpose of elevating the slide, 68, and the secondary knitting cams to draw the latter out of operative position while knitting the leg, the slide is provided with a block, 111, to which is secured a vertically disposed lifting rod, 112, the lower end of which is engaged by one end of a lifting lever, 113, connected by intermediate links, or levers (not shown), with a cam actuated lever, indicated at 115 in Fig. 4, for example, one end of which is engaged at the proper time by a cam on a cam wheel, 117, located on the pattern wheel shaft, for raising the end of the lever 113, which engages the rod, 112, at the proper times, after knitting the instep and at the beginning of the heel pocket.

The knitting cams, 62 and 63, are also directly connected to a radially movable block, indicated at 75, mounted in the slide, 68, and capable of moving outwardly from the axis of the needle cylinder for the purpose of throwing the cams out of operative position when desired, automatically after the knitting of the loopers' edge so as to permit leveling of the needles for transferring the rib, and for the latter purpose a horizontally swung lever, 79, engaging a pin, 81, depending from the block, 75, is provided, the said cams being normally held in their operative or inwardly extended positions by a spring, 77. All of the parts thus far described are of known construction and operation and are illustrated and described in the Lawson patent above referred to, and it will be seen that by means of the lever, 113, the slide, carrying with it the secondary knitting cams, 62 and 63, may be elevated, under the control of the pattern mechanism or pattern wheel shaft to prevent interference with the stitches formed by the primary cams. When the lever, 113, descends and releases the rod, 112 after the knitting of the heel pocket by the short butt needles, the slide, 68, should descend until it is arrested by the set screw, 72, but as before stated, in actual practice it very frequently happens that the cams do not descend when released frequently due to the gumming of oil on the parts, with the result that additional

courses, sometimes through the entire instep of a stocking, for example, are knit with the smaller or tighter stitch, thus producing a shorter fabric than desired and resulting in defective work.

According to my invention I provide means for positively pulling down the slide, 68, after it has been released by the lever, 113. To this end I prefer to provide the slide, and in this instance, the block, 111, carried thereby, with a laterally extending arm, 220, having an aperture in its outer end for the connection thereto of a vertically disposed connecting rod, 218, which extends downwardly to and is adjustably connected with a boss, 217, carried by a laterally disposed arm, 216, of a lever, 215, pivotally secured to the main frame, and in this instance, supported on the same pivot, indicated at 222, as the lever, 115, the said lever, 215, being provided with a bearing portion, 223, which is adapted to engage one or more cam grades or projections, two of such cams, 219 and 219^a, being shown herein, on a cam wheel, 224, on the pattern wheel shaft, 9, said shaft also carrying the cam wheel, 117. The cam wheels, 117 and 224, may be separate cam wheels or may be formed integrally, if desired. The connecting rod, 218, preferably extends through a hole in the boss, 217, and is adjustably secured in position by a set screw, 225. In order that the downward pull exerted on the rod, 218, may always draw down the slide, 68, and the knitting cams, 62 and 63, no matter what position the adjusting screw, 72, may occupy, and at the same time in order to prevent the breaking or bending of the arm, 220, or other part of the mechanism, I provide the rod, 218, with a head or enlargement, 221, between which and the arm, 220, is inserted a spring, 226. This spring is of sufficient stiffness so that when the rod, 218, is drawn downwardly, by the action of the cams, 219 and 219^a, and lever, 215, will positively insure the drawing down of the block, 111, and slide, 68, and the knitting cams, 62, 63, under all conditions, no matter whether the parts are gummed with oil so as to work stiffly or otherwise, and at the same time there will be sufficient resiliency in the spring to permit a slight yielding thereof, when the slide, 68, engages the set screw, 72, and is arrested in its lowest adjusted position. This spring does not flex under any conditions in the action of drawing down the slide 68 and the secondary knitting cams unless of course the set screw 72 is adjusted relatively high to produce a comparatively short stitch, in which event the spring will slightly give to prevent breakage of parts. It will be understood, however, that the spring may be entirely omitted provided of course that every time the operator adjusts the set screw 72 to ob-

tain a stitch of predetermined length or tightness, he makes a corresponding adjustment of the rod 218 in the boss 217. By the use of the spring this fineness of adjustment by unskilled operators is unnecessary and the action of the connection in drawing down the cams is positive to the point where the slide contacts with the stitch adjusting screw. In this way, that is by the proper adjustment of the rod, 218, with respect to the boss, 217, to insure a slight compression of the spring, 226, when the cams are in their lowest position, the correct operation of the device and the proper lowering of the cams at the desired point in the cycle of operation of the machine is certainly and positively secured.

In the operation of a stocking knitter having my invention applied thereto, the following procedure may be followed for example.

In knitting the leg of the stocking, during which time the machine will ordinarily operate circularly to produce circular knitting, the knitting cams, 62 and 63, are inoperative and are raised by lever, 113, into their highest position, the knitting all being done through the control of the primary cams and all of the needles.

On starting to knit the instep portion of the stocking, the rear portions of the courses of which are above the heel, the cams, 62 and 63, are restored to operative position, and released by lever, 113, and this portion of the stocking is preferably knit as a split fabric by reciprocating work on all of the needles of the circular series. Therefore, on starting the knitting of the instep, one of the cams, 219, 219^a, (as cam 219) comes into action and positively draws down the secondary knitting cams, 62 and 63, to a predetermined stitch position controlled by the set screw 72, as soon as they are released by lever, 113, so that these stitch cams will draw stitches of predetermined length while knitting the instep which correspond as nearly as possible to the stitches drawn in the leg portion of the stocking.

At the commencement of the heel portion, the stitch cams, 62 and 63, are again raised and thrown into inoperative position, and the heel is knit in the usual manner by reciprocating knitting and narrowing and widening on a section of the circular series of needles, namely the short butt needles, the other section of which remain inoperative and hold their stitches.

On the completion of the heel, the cams, 62 and 63, are again restored to operative position and released by lever, 113, and are positively drawn down by one of the cams, 219, 219^a, (as cam 219^a) to the predetermined position for knitting the instep of the foot, which is preferably knit as a split fabric by reciprocating knitting on all the needles of

the circular series, thus insuring the knitting of the instep with stitches of predetermined size, and positively determining the length of the foot portion.

The toe pocket is knit in the usual manner by reciprocating knitting and narrowing and widening on a section of the needles, and the usual raveling courses are knitted and the stocking is finished in the usual way by looping. The pattern mechanism is set for producing a definite number of courses through the leg and instep, and through the foot between the heel pocket and the toe pocket, thereby determining the standard size of the sock, and obviously, if the number of courses in the instep and foot for which the pattern mechanism is set to produce, say a number nine sock, were knitted with a finer stitch than that intended, the result would be the production of a stocking which would be very materially shorter in the instep and foot than intended and required to produce a number nine sock, and if sold as a number nine, would not give satisfaction to the consumer. In practical operations of machines not provided with my invention, I have found many cases in which the knitting cams failed to return to their proper positions, even where auxiliary springs were employed, with the result that the stockings produced varied as much as a half inch or more from the standard size, and previous to my invention, it was necessary to carefully inspect the product from every machine in order that no shorts should be passed on as true standard sizes through the finishing processes. This necessary inspection has heretofore caused additional expense in producing the hosiery, besides creating an element of uncertainty in the operation of the machines. With my invention the machines can be operated for any given size with the certainty that the sizes for which the machine is set will be certainly and continuously produced, and this additional step of inspection, with its incident cost, is entirely obviated.

While I have shown the cam wheel, 224, provided with two cams, 219 and 219^a, in this instance for bringing my improved cam restoring means into operation twice during the knitting of the stocking, it is to be understood that my invention is not limited to any particular number of such cams and that one or more may be employed according to the work produced by the machine.

What I claim and desire to secure by Letters Patent is:

1. In a circular stocking knitter provided with a circular series of needles, and secondary stitch forming cams movable vertically, and means for arresting the cams in their lowest position to cause them to draw stitches of predetermined size, of means for elevating said cams, and means for positive-

ly drawing down said cams at a predetermined point in the cycle of the machine, into contact with said arresting means to prevent the knitting of courses thereby with 5 a tighter stitch than desired and the consequent variation in the length of the section of the stocking knit thereby, said means constructed to yield when the cams are brought into contact with the arresting 10 means so as to prevent breakage of parts.

2. In a circular stocking knitter provided with a circular series of needles and secondary stitch forming cams movable vertically and adjustable, means for arresting the 15 cams in their lowest position to cause them to draw stitches of predetermined size, which may be varied by the said adjustable arresting means, of means for elevating said cams, and means including adjustable portions 20 for positively drawing down said cams at a predetermined point in the cycle of the machine, into contact with said adjustable arresting means to prevent the knitting of courses thereby with a tighter stitch than desired, and the consequent variation 25 in the length of the section of the stocking knit thereby, said means constructed to yield when the cams are brought into contact with the arresting means so as to prevent breakage 30 of parts.

3. In a circular stocking knitter provided with a circular series of needles and secondary stitch forming cams movable vertically, and means for arresting the cams in their 35 lowest position to cause them to draw stitches of predetermined size, of means for elevating said cams, and means for positively drawing down said cams into engagement with the said arresting means, said means being called into action at the commencement 40 of the knitting of the instep portion of the stocking, to insure the knitting of the foot portion with stitches of predetermined size, and to insure the production of stockings 45 of uniform standard size, said means constructed to yield when the cams are brought into contact with the arresting means so as to prevent breakage of parts.

4. In a circular stocking knitter provided 50 with a circular series of needles and secondary stitch forming cams movable vertically, and adjustable means for arresting the cams in their lowest position to cause them to draw stitches of predetermined size, which 55 may be varied by the said adjustable arresting means, of means for elevating said cams, and means including adjustable portions for positively drawing down said cams into contact with said adjustable arresting means, 60 called into operation at the commencement of the knitting of the instep portion of the stocking to insure the knitting of the foot portion with stitches of predetermined size for which said arresting means is adjusted, 65 to insure the knitting of the foot of the

stocking with stitches of predetermined size and the production of stockings of uniform standard predetermined size, said means constructed to yield when the cams are brought into contact with the arresting 70 means so as to prevent breakage of parts.

5. In a circular stocking knitter provided with a circular series of needles, and secondary stitch forming cams movable vertically, and means for arresting the cams in their 75 lowest position to cause them to draw stitches of predetermined size, of means for elevating said cams, and means including a rotary cam, a lever operated thereby, and operative connections from said lever to said 80 knitting cams for positively drawing down said knitting cams at a predetermined point in the cycle of the machine into contact with said arresting means to prevent the knitting of courses thereby with a tighter 85 stitch than desired, and the consequent variation in the length of the section of the stocking knit thereby, said means constructed to yield when the cams are brought into contact with the arresting means so as to prevent 90 breakage of parts.

6. In a circular stocking knitter provided with a circular series of needles and secondary stitch forming cams movable vertically, and adjustable means for arresting the cams in their lowest position to cause them to draw stitches of predetermined size, which may be varied by the said adjustable arresting means, of means for elevating said cams, and means including adjustable portions, including a horizontal arm operatively connected with said knitting cam, a rotary cam, a lever operated thereby, a connecting rod engaging said horizontal arm and connected with said lever, and means for adjusting 100 said rod with respect to said arm and lever for positively drawing down said knitting cam at a predetermined point in the cycle of the machine into contact with said adjustable arresting means to prevent the knitting 105 of courses thereby with a tighter stitch than desired, and the consequent variation in the length of the section of the stocking knit 110 thereby.

7. In a circular stocking knitter provided 115 with a circular series of needles and secondary stitch forming cams movable vertically, and means for arresting the cams in their lowest position to cause them to draw stitches of predetermined size, of means for elevating said cams, and means called into operation at a predetermined point in the cycle of the machine for positively drawing down said cam into contact with said arresting 120 means, said drawing down means having a movement greater than necessary to effect the desired movement of the cams, and a part in the connection between said means and the knitting cam to positively insure the drawing down of the knitting cams into con- 125

tact with the arresting means and to then yield to avoid subjecting the parts to undue strain or breakage.

8. In a circular stocking knitter provided with a circular series of needles and vertically movable secondary knitting cams for regulating the size of the stitches drawn by the needles, a vertically movable slide supporting said knitting cams, hand operated adjusting means for limiting the downward movement of said slide to determine the maximum size of stitch drawn by the needle, pattern controlled elevating mechanism for said slide and means for positively drawing down said slide and knitting cams when released by said elevating mechanism, including a horizontal arm secured to said slide and provided with an aperture therethrough, a pull rod extending through said aperture, a spring interposed between said pull rod and said arm, a pull-down lever

having one end adjustably connected to said rod and a pull-down cam controlled by the pattern mechanism, for engaging the other end of said pull-down lever, and positively 25 lowering said slide into engagement with the said hand operated adjusting means.

9. In a circular stocking knitting machine, the combination with vertically movable secondary knitting cams, means for elevating 30 the cams and adjustable means for arresting the descent of the cams to determine the size of the stitch drawn thereby, of mechanism for positively drawing down said cams at a predetermined point in the cycle of the 35 operation of the machine into contact with said arresting means, and means included in said mechanism for yieldingly accommodating the adjustment of said arresting means. 40

In testimony whereof I affix my signature.

HAMILTON LEE DAVIS.
